UNITED STATES PATENT OFFICE.

WILLIAM D. RANNEY, OF COLUMBUS, OHIO.

FURNACE-ARCH.

1,289,262.

Specification of Letters Patent. Patented Dec. 31, 1918.

Application filed January 29, 1918. Serial No. 214,323.

To all whom it may concern:

Be it known that I, WILLIAM D. RANNEY, a citizen of the United States, residing at Columbus, in the county of Franklin and 5 State of Ohio, have invented a certain new and useful Improvement in Furnace-Arches, of which the following is a specification.

This invention relating to furnaces has for its object to provide an improved construction of fire box arch of simple and 10 economical construction that can be erected without the aid of expert workmen. As now generally used such arches are "hand sprung," that is they are built of fire brick 15 over a specially erected form.

The expansion and contraction of a hand sprung arch over a furnace fire and the end thrust due to the weight of the arch on the side walls has a tendency to cause it 20 to fall and shortens the life of the arch, thereby necessitating a rebuilding or removal of the entire arch and side walls. The present invention obviates these 25 troubles and provides an arch which can be economically and easily repaired by replacing any of its parts.

The invention is embodied in the construction shown in the accompanying drawings and set forth in the following description, the features of novelty being finally 30 claimed.

In said drawings—

Figure 1 is mainly a vertical longitudinal section of a boiler furnace equipped with 35 my invention.

Fig. 2 is a top plan view of the arch structure.

Fig. 3 is a front elevation of the arch structure as viewed from the left hand side 40 of Fig. 2.

Fig. 4 is a perspective view of one of the blocks used in the arch structure.

In the views 5 designates the side walls of the furnace between which is supported 45 an ordinary boiler 6.

The character 7 designates the opening through which fuel is supplied to the fire box, said opening being provided with the usual door 8. Supported between the door 50 arch and the ordinary bridge wall 9 is a

grate of any suitable construction but preferably of the shaking variety inclined to about fifteen degrees rearward. Below the grate is the ash pit 10 to which access is had through an opening in the door arch 55 provided with a door 10^a.

In the fire box above the grate I provide an arch including a frame consisting of a series of bars 11 resting as shown, removably at their upper ends upon a plate 12 60 inserted in the crown of the door arch and at their lower ends removably as shown upon a cross bar 13 supported at its opposite ends in the side walls of the furnace. The bars 11 are arranged parallel to each other 65 and should have a dip rearward of about fifteen degrees from the horizontal. The lower ends of said bars are bifurcate to straddle the cross bar 13. Removably supported upon and between the bars 11 are 70 blocks 14 which have end lips 14^a to rest on the upper edges of the adjacent bars 11. These blocks are made of such dimensions as to be easily handled but so as to practically fill the frame made up of the bars 75 11 by use of blocks of uniform dimensions. These blocks are made of fire clay or other refractory material or compound adapted to withstand a high temperature. It will be observed that this arch can be taken down 80 and repaired or replaced in any of its parts without destruction of the door arch or side walls.

Changes can be made in the forms and sizes of the parts without departing from 85 the gist of the invention as claimed.

What I claim is:

In combination with the fire box and door arch of a boiler furnace, a plurality of parallel bars extending rearwardly in the 90 fire box, each of said bars resting removably at its forward end upon the crown of the door arch and having its rear end bifurcate, a bar supported between the side walls of the fire box and receiving and supporting 95 the bifurcate ends of said parallel bars, and blocks of refractory material having lips resting removably upon said parallel bars to support the blocks between them.

WILLIAM D. RANNEY.
